US00D455088S

(12) **United States Design Patent**
Beha

(10) Patent No.: **US D455,088 S**
(45) Date of Patent: ** Apr. 2, 2002

(54) **ELECTRICAL TEST AND MEASURING DEVICE**

(75) Inventor: **Christian Beha**, Glotttal (DE)

(73) Assignee: **Ch. Beha GmbH Technische Neuentwicklungen**, Glotttal (DE)

(**) Term: **14 Years**

(21) Appl. No.: **29/142,008**

(22) Filed: **May 18, 2001**

(51) LOC (7) Cl. **10-04**

(52) U.S. Cl. **D10/78**

(58) Field of Search D10/78; 324/72.5,
324/115, 133, 149

(57) **CLAIM**

The ornamental design for an electrical test and measuring device, as shown and described.

DESCRIPTION

FIG. 1 is a bottom view of a electric test and measuring device showing my new design;

FIG. 2 is a top plan view thereof;

FIG. 3 is a right side elevational view thereof;

FIG. 4 is a left side elevational view thereof;

FIG. 5 is a rear elevational view thereof; and,

FIG. 6 is a front elevational view thereof.
